UNITED STATES PATENT OFFICE.

CLARENCE W. UTZMAN, OF CHICAGO, ILLINOIS, ASSIGNOR TO UNITED STATES GYPSUM COMPANY, OF CHICAGO, ILLINOIS, A CORPORATION OF ILLINOIS.

WALL CONSTRUCTION.

Application filed November 26, 1923. Serial No. 676,903.

To all whom it may concern:

Be it known that I, CLARENCE W. UTZMAN, a citizen of the United States, residing at Chicago, in the county of Cook and State of Illinois, have invented new and useful Improvements in Wall Constructions, of which the following is a specification.

This invention relates to improvements in building construction and more particularly to the manner and material used in erecting a fire resisting wall construction.

In erecting side walls, ceilings and partitions, it has been customary to provide wooden studs as a backing for the nailing of wooden or expanded metal laths over which a coating of wall plaster is applied. Metal angle irons, such as channel irons, have been substituted for the metal studs with plaster boards or expanded metal laths secured thereto by clips, or otherwise, and then covered with wall plaster in erecting walls that will possess greater fire resisting qualities than the wooden stud and wooden lath walls, for with the use of wood it takes a less degree of heat penetration to char and finally ignite the wood laths and studs than it does to cause the metal studs to deform and buckle.

It is an object of this invention to provide a wall construction that will be even more fire resisting than the metal backing construction by the employment of a backing of greater fire resisting property than uncovered metal and securing thereto plaster wallboards in lieu of lath and plaster and at the same time provide a positive means of securing the parts together in such a manner as to form substantially a monolithic wall surface not defaced by the small hair line cracks, known as "map cracks," usually appearing in walls employing plaster wallboards in the place of lath and plaster.

The advantages of such a wall construction are obvious, for not only is a uniform flat unbroken and unmarred monolithic wall surface presented without the time and labor of applying the customary coating of wall plaster but it also will provide a wall, ceiling or partition of much greater fire

resisting qualities than the metal backing construction, and another advantage is that the fire resisting backing and plaster wallboards contemplated in this invention may both be sawed and fitted in the same manner as the wooden construction herebefore mentioned.

This invention contemplates the use of gypsum lumber for the backing of wallboard the nature of which board will permit the accomplishment of the above described objects. The gypsum lumber herein referred to is preferably a reinforced gypsum body having a fibrous covering bonded thereto, although the reinforcement may be omitted or the covering omitted without departing from the scope of this invention. The gypsum lumber, as above described, possesses greater fire resisting qualities than metal channel iron backing on account of its low conductivity, and it will take a greater degree of heat to reduce its strength and shape than the degree of heat necessary to cause the metal backing to deform or buckle. Furthermore, while gypsum lumber will retain the usual nails necessary to hold plaster wallboard in place upon wooden studing, the gypsum lumber being of the same material as plaster wallboard will allow of a cementing or attaching of the two together by an adhesive which will unite the contacting surfaces so that substantially a monolithic surface of wall will be provided. It being impractical to bring the adjacent wallboards close enough together in erecting to prevent cracks or openings between their edges, on account of the unevenness of the manufactured articles, it has been customary to fill such cracks or openings with a filler known as "finisher" or "crack filler" but with the wooden or metal backing such crack filler or finisher being exposed to the air on both sides of the crack will dry out from both sides in setting and leave a line of demarkation where the crack occurs but when the bottom of the crack or opening is sealed by the gypsum lumber stud of the same material as the edges of the wallboard the crack filler or finisher dries evenly and continues a smooth surface

from one board to the other. The hair line or map cracks in the crack filler between wallboards nailed on wooden studs are caused by the pulling apart of the boards, 5 however small the motion may be, from many causes, as the nails will bend or the wood expand or twist but when the boards are united surface to surface with the stud by an adhesive such small movement is 10 prevented.

While the preferred form of this invention is illustrated upon the accompanying drawing yet minor detail changes may be made without departing from the scope 15 thereof.

In the drawings:

Figure 1 is a view in front elevation of a part of a wall constructed in accordance with this invention, with parts broken away.

20 Figure 2 is a top plan view of Figure 1.

Figure 3 is a similar view of a modified form of this invention.

Figure 4 is a view in side elevation of Figure 1 in course of construction in which 25 one board has been placed in position upon the stud.

In the embodiment of this invention as illustrated the gypsum lumber stud is of the same shape and dimensions as the customary wooden stud or backing and may be secured in position in the same manner as the wooden backing. In this form the gypsum stud is shown as comprising a body 1 of gypsum having a paper covering 2, of the 30 same character as plaster wallboard covering, bonded thereto. The plaster wallboards 3 and 4 are of the type having gypsum body with paper covering upon both side faces 35 and passing over the longitudinal abutting 40 edges of each board.

In erecting the wall, ceiling or partition in accordance with this invention the gypsum lumber having been secured in place, the surface of the lumber over which the plaster wallboard is to be placed is covered with a coating 5 of adhesive, such as flour paste, 45 silicate of soda, glue or any other desirable adhesive which will unite the paper of the stud to the paper of the wallboard. The 50 wallboards are then placed thereover in the usual manner and the surface of the wallboard is held in close engagement with the adhesive by nailing the wallboard thereto so that the drying of the adhesive will bond 55 the stud and wallboard throughout their contacting surfaces and form an air tight backing between the abutting edges of the adjacent wallboards. Heretofore it has been customary to arrange the spacing of 60 the studding forming the backing for wallboards so that the edges of the adjacent boards come together over a stud with one or more studs in between and nail the wallboard to the stud about each adjacent edge 65 with nails closely spaced, for example about

three inches apart, and to the intermediate stud or studs at a greater distance, for example about nine inches apart.

It has been found that it is not necessary to apply the adhesive to the intermediate 70 studs and that a greater spacing of the nails along the adjacent boards, about that of the customary spacing on the intermediate studs, is sufficient to hold the edges in contact with the adhesive so that a complete 75 bond will be formed throughout their length.

On account of the small irregularities in the edges of wallboards it has been found 80 advisable to space the abutting edges of adjacent boards a small distance apart and fill the aperture so formed with a substance similar to the plaster body combined with an adhesive which is smoothed over in the plane of the flat surfaces of the boards and 85 may be covered with the decorating medium applied to the exposed surface of the wall or ceiling without indicating its presence. However such crack filler or finisher ordinarily dries out from both sides of the crack 90 and causes a slight depression along the line of the adjoining boards and during settling or vibration of the building or upon the expansion or contraction of the wooden backing, forming fine hair line or map cracks between the boards. In the wall as erected in accordance with this invention when the crack filler or finisher 6 is applied between the boards (the distance between the boards 95 in Figures 1 and 2 is exaggerated), the boards being bonded to the gypsum lumber forming an air tight joint, only the outer surface of the crack filler or finisher is in contact with the atmosphere and will dry 100 from that side only and may be readily applied in such quantity that it will dry out with its surface in line with the surfaces of the adjoining boards and when the boards are decorated its presence will not be discernable.

Furthermore, the entire margins of the adjoining edges being bonded throughout to the same gypsum lumber backing and to 110 each other vibrations or other slight movements of the building can not impart sliding movements of the adjoining boards over the backing, such movements being the cause of map cracks, the finisher or crack filler will not show the hair line cracks as in other 115 constructions, in fact the wall, ceiling, or partition constructed in accordance with this invention presents to the interior of the room 120 substantially a monolithic surface.

Figure 3 illustrates another form of this 125 invention particularly adapted for the erection of partitions in which the gypsum lumber is provided with depressions 7, slightly greater in depth than the thickness of the wallboard to be applied, arranged along the opposite edges of the opposite sides, as 130

shown, so that a portion 8 of the gypsum lumber will enter between the adjacent edges of the boards and separate the edges from each other. In this case the adhesive 5 is applied to both surfaces of each depression and the boards applied and held in contact with both surfaces of each depression by spaced apart nails, as shown, the boards 3 and 4 being applied on one side and the boards 9 and 10 being applied on the opposite side of the stud. The depth of the depressions are such that when the under sides of the boards therein are bonded to the gypsum stud by the adhesive their outer surfaces will be in line with the surface of the interposed portion 8 of the stud and with each other. In case of irregularities in the widths of the boards or gypsum studs causing a gap between the edges of the boards and side walls of the depression not filled by the adhesive crack filler or finisher may be employed in the same manner as above described or it may be desirable to arrange the spacing of the gypsum lumber so that such a gap will customary occur and will be customary filled by the finisher or crack filler which in this construction will act in the same manner as in the construction heretofore described.

In carrying out this invention it is not necessary that the plaster wallboards are of the bound edge type nor is it necessary that they be covered with fibrous material. A suitable adhesive may be applied to the fibrous covered stud to bond the margins of the uncovered plaster boards thereto and the finisher will bond raw plaster edges to each other in the same manner on the bound edges. Neither is it necessary that the gypsum lumber be provided with a fibrous covering for the same reason. It being understood that any construction whereby the backing for walls, ceilings, partitions or the like may be glued, cemented or otherwise form an air tight permanent jointure to the composition or other boards attached thereto and the abutting edges of such boards be bonded to each other so that the wall, ceiling or partition or the like when so erected will present substantially a monolithic surface is included within the scope of this invention.

This invention also contemplates the application of expanded metal lath to the gypsum lumber backing and covering the lath with wall plaster which plaster will bond the metal lath to the gypsum studs at the time it embeds the metal lath and forms therewith substantially a monolithic wall construction presenting an unbroken wall surface. A wall, ceiling or partition so constructed will be more fire resisting than metal lath with metal angle iron backing, or plasterboard with metal angle backing, covered with wall plaster and even more fire-

resisting than a similar construction employing plaster wallboard and gypsum lumber backing, as herein described. On account of the low conductivity of the gypsum in the gypsum lumber withstanding a greater degree of heat before it disintegrates and fails under the stresses and strains to which it is normally subjected in its erected position than the degree of heat that will cause the metal backing to deform, buckle or fail, and as this gypsum lumber when taken in combination with metal lath, in which the metal of the lath is under different stresses and strains than the backing, and to which the plaster when applied forms a mechanical key holding the wall in place, when subjected to excessive heat will exist for a longer time without disintegrating than plaster board plastered over or plaster wallboard without a coating and will therefore provide a more fire-resisting wall than the other forms described.

What I claim is:—

1. A fire resisting wall comprising a backing of gypsum lumber, an adhesive thereon and wall sections secured to the lumber contacting with the adhesive and bonded thereby to the lumber.

2. A fire resisting wall comprising a backing of gypsum lumber, an adhesive applied thereon, wall sections held thereagainst and bonded to the lumber, and means applied between the abutting edges to the sections bonding them to each other.

3. A fire resisting wall comprising a backing of gypsum lumber, an adhesive applied thereon, wall sections of fire resisting material having their adjacent edges laying over the gypsum lumber, contacting with the adhesive thereon and bonded by the adhesive to said lumber.

4. A fire resisting wall comprising a backing of gypsum lumber, fire resisting wall sections having their abutting edges laying over said backing, an adhesive between the lumber and sections bonding one to the other, and means between the abutting edges of the sections contacting therewith and with the adhesive covered lumber therebetween bonding the edges to each other and to the lumber thereby presenting a wall surface substantially monolithic in structure.

5. A fire resisting wall construction having a fire resisting backing comprising gypsum lumber studs and gypsum wallboard sections with their abutting edges laying over the studs, an adhesive between the studs and contacting portions of the wall sections, bonding them to the studs and gypsum filler between the abutting edges of the wallboards bonding said edges to each other and bonding to the stud presenting a monolithic wall surface.

6. A fire resisting wall construction having a fire resisting backing comprising

gypsum lumber and studs and gypsum wall board sections with their contiguous edges laying over the studs, said studs having depressions to receive the said edges of the contiguous boards aligning the outer surfaces of the said boards and projecting portion of the stud, an adhesive between the studs and contacting portions of the wall

sections bonding them to the studs, and between the contiguous edges of the wall boards and projections of the studs bonding the margins and edges of said wallboards to the studs presenting a monolithic wall surface.

CLARENCE W. UTZMAN.
